 L. S. D. Inc., Dayton, Ohio, a corporation of
 Ohio

Application May 31, 1938, Serial No. 210,937

8 Claims. (Cl. 141—9)

This invention relates to new and useful improvements in racks and pertains more particularly to racks of a character adapted to be employed for supporting all types of dishes, glassware, and silverware in washing machines of the character disclosed and claimed in my application Serial No. 134,911, filed April 3, 1937, which has since matured into Patent No. 2,137,971, of November 22, 1938.

10 The primary object of this invention is to provide a rack which is adapted for supporting dishes, glassware, and silverware in proper relatively spaced relation and at the most effective angles to permit washing, rinsing, and/or drying of the same by means of suitable fluids projected at a high velocity and in a finely atomized condition from a zone arranged beneath the rack.

15 A further important object of the invention is to provide a rack of the aforementioned character which is formed entirely of wire strands of proper gauge and with the various strands shaped to produce supporting surfaces for holding flat dishes and bowls on edge and cups and glasses in an inverted and inclined position.

20 Another object of the invention is to provide a rack of the above mentioned type which is formed with portions or sections constructed and arranged in a manner to enable them to be employed as supports for different kinds of dishes and glassware.

25 Other objects and advantages of the invention will be apparent during the course of the following description.

30 In the accompanying drawings forming a part of this specification and in which like numerals are employed to designate like parts throughout the same:

Figure 1 is a top plan view of the rack device embodying this invention.

35 Figure 2 is a side elevational view of the rack which is taken from the side nearest the observer in Fig. 1.

40 Figure 3 is an end elevational view taken at the left-hand end of Fig. 1.

45 Figure 4 is a side elevational view taken at the opposite side to the view shown in Fig. 2, and

Figure 5 is an end elevational view taken at the right-hand end of Fig. 1.

The rack embodying this invention is formed 50 entirely of wire strands of proper gauge to provide the desired degree of strength and rigidity. Wherever the various strands are connected or attached to each other, the joints may be soldered, welded, brazed, or attached in any other suitable manner. In plan view, see Fig. 1, the rack is

5 of generally rectangular formation. It is defined with reference to its horizontal margins by means of a main frame which is designated in its entirety by the reference character 6. This frame is formed of a single strand of wire shaped to provide the straight side 7, see Fig. 2, the straight end 8, see Fig. 3, the side disclosed in Fig. 4 which includes the stepped portions 9 and 10, and the straight end 11, see Fig. 5. At each of the four corners of the rack, the main frame 6 is supported on legs 12, 13, 14 and 15. The side 7 is provided with an additional leg 16 while the portion 10 of the remaining or opposite side is provided with a leg 17. These various legs are formed of short lengths of wire which are bent 10 into substantially V- or U-shape with the extremities attached to the main frame parts and with the bights arranged to engage the surface on which the rack is supported.

15 By inspecting Fig. 1, it will be seen that substantially one-half of the area covered by the main frame 6 is taken up with parallel channels 18, see also Figs. 2 and 4, which are intended to receive flat dishes supported on edge. By "flat dishes," I mean dinner dishes, salad dishes, 20 saucers, and the like. These channels 18 are defined at their top by the parallel, spaced strands 19 which are arched to provide the generally horizontal extending top portions 20 and the depending end extremities or legs 21. By inspecting 25 Figs. 2 and 4, it will be seen that the end extremities or legs 21 are inclined to the perpendicular so that they do not occupy the same vertical plane as their respective top portions 20.

30 By inspecting Figs. 1, 2 and 5, it will be seen that each one of the top portions of the strands 19 is shaped at one side of the frame to provide the perpendicular portion 22 and the inclined portion 23 which connects the lower end of the perpendicular portion 22 to the upper end of the 35 adjacent extremity or leg 21. The respective perpendicular portions 22 of all of the strands 19 and the horizontally inclined portions 23 of all of said strands are arranged in the same plane. The horizontally inclined portions 23 collectively form a shelf which will support a bowl, or the like, when the portions of the channels 18 occurring between these strands parts 23 are not obstructed or occupied by dishes positioned 40 within the said channels. Due to the inclination 45 of the strand portions 23, a bowl, or the like, positioned on its side with its cavity exposed to the center of the rack will be inclined or will lean toward the outside. This positioning of a bowl will permit the interior of the same to be 50 55

more effectively treated by the fluids projected from a zone positioned beneath the rack.

The bottoms of the channels 18 are bridged by means of a plurality of transversely extending strands 24, see Figs. 1, 2, 4 and 5. These strands have their ends 25 bent upwardly for connection at their upper extremities with the outside strands 19. Figs. 1 and 5 also disclose the upstanding end portions 25 of the transverse strands 24 as being connected to the end member 11 of the main frame 6. By inspecting Figs. 1, 2 and 4, it will be seen that each one of the transversely extending strands 24 has its horizontally extending portion repeatedly, reversely bent to form angles 26. These angles are provided in each transverse strand 24 for each one of the channels 18. By carefully examining Figs. 2 and 4, it will be seen that these angles 26 are slightly laterally offset with respect to the central vertical plane of each channel 18. The flat dishes which are stood upon edge in the channels 18 have these edges seated in the angles 26 and due to the offset positioning of these angles, the dishes will be inclined or will slope laterally inwardly of the adjacent end of the rack so that when their concaved sides are presented toward the center of the rack, these concaved sides or surfaces will be more effectively exposed to the treatment fluids which are projected upwardly from a zone located beneath the frame 6 of the rack. To properly brace and interconnect the intermediate portions of all of the strands 19 and 24, perpendicular brace strands 27 are provided at each point where the strands 19 and 24 intersect each other. These perpendicular bracing strands are disclosed very clearly in Fig. 4.

In the right-hand portion of the disclosure of Fig. 3, there is shown a wire strand which is designated in its entirety by the reference character 28. This strand includes a perpendicular end portion 29 which is secured at its extremity to the side 7 of the main frame 6. From the upper end of the portion 29, the wire is bent into an inclined, generally horizontally extending portion 30 which connects with a second perpendicular portion 31 arranged in parallelism to the portion 29. From the lower end of the second perpendicular portion 31, the wire is arranged in a second inclined, generally horizontally extending portion 32. The lower end of the portion 32 connects with a generally perpendicular extending portion 33 which is considerably longer than either of the portions 29 and 31.

In the lower left-hand portion of the rack disclosed in Fig. 1, there are shown five of the wires 28. Each one of these wires is shaped in the manner illustrated in Fig. 3. All of the portions 30 of the various strands 28 collectively form an inwardly sloping shelf which is especially adapted for supporting bowls. The portions 32 of the several strands 28 also collectively function to form a shelf for receiving bowls. These portions 30 and 32 are properly inclined to position bowls to permit the cavities of the same to be properly treated with fluids employed for washing, rinsing and drying the same. It will be noted by inspecting Figs. 1 and 2 that the strand portions 30 are in horizontal alignment with the strand portions 23 of the channel forming wires 19. These strand portions 23 and 30, therefore, collectively form a single shelf which extends the full length of the rack frame.

To act as an abutment along the lower edge of the shelf formed by the strand portions 30, a wire strand 34 is provided and is connected

at the extremity of its outer downwardly bent end to the outside strand 28. The remaining end of the strand 34 is connected at 35 to the horizontal portion 20 of the inside strand 19. To provide a proper degree of rigidity, two perpendicular brace strands 36 extend between the horizontal portion of the abutment strand 34 and two of the shelf forming strands 28. These bracing strands are disclosed in Figs. 1 and 3. A plurality of suitably positioned, horizontally extending cross bracing strands 37 are provided for connecting the shelf forming strands 28, as best illustrated in Figs. 1, 2 and 3.

Connected to the various perpendicular portions 33 of the several shelf forming strands 28 is a strand 38 which is shown best in Figs. 1, 2 and 3. This strand 38 has its inner end portion bent downwardly to permit it to be connected at 39, see Figs. 1 and 2, to the portion 20 of the adjacent channel forming strand 19. In Figs. 1, 3 and 5, there is shown a strand 40 which has its outer end bent downwardly, as at 41, see Figs. 3 and 5, for connection with the frame end 8. The horizontally extending portion 42 of this strand is arranged in parallelism with the aforementioned strand 38, but at a slightly lower level. Extending between the horizontal portion 42 of the strand 40 and the opposite portion of the strand 38 are short, shelf forming strands 43. Due to the difference in levels between the portions 42 and 38, these shelf forming strands 43 are inclined. This shelf is intended primarily for supporting glasses or cups in an inverted, inclined position.

The various figures also disclose two strands 44 which interconnect the two-strand portions 38 and 42 and act as a support for a basket 45 which is intended to hold silverware standing on end.

In Figs. 1, 3 and 4, there is disclosed a plurality of strands 46 which are connected at their lower ends 47, see Fig. 4, to the side frame portion 9. From these lower ends 47, the strands extend upwardly on an incline to form the portions 48 which collectively act as an additional shelf for supporting desired dishes, or the like. From the upper ends of the sloping portions 48, the strands 46 extend upwardly at a sharper angle to form the parts 49 which are joined at 50, see Fig. 1, to the horizontal portion 42 of the strand 40.

In Fig. 3, there is disclosed a substantially L-shaped strand 51 which overlies the inclined shelf formed by the portions 48 of the strands 46. In Fig. 1, two of these L-shaped strands 51 are disclosed. The opposite ends of these strands 51 are connected to the side frame portion 9 and to the horizontal portion 42 of the wire 40, respectively. A hinged shelf 52 is pivotally connected to the horizontal portion 42 of the strand 40, as best illustrated in Figs. 1, 3 and 4. Figs. 1 and 3 clearly illustrate this pivoted shelf 52 in full line position to overlie the inclined shelf formed by the portion 48 of the strands 46. Fig. 3 discloses the shelf in a dotted line position where it is thrown back to uncover the shelf formed by the strand portions 48. When in its full line position, this pivoted shelf 52 will function as a support for glasses or cups. When not needed for these objects, it may be thrown back to make available the inclined shelf which lies therebeneath. It is possible, also, to position cups and small bowls on the shelf formed by strand portions 48 and, after closing the shelf 52

52, to position glasses and cups on the latter shelf.

It is to be understood that the form of this invention herewith shown and described is to be taken as a preferred example of the same, and that various changes in the shape, size, and arrangement of parts may be resorted to without departing from the spirit of the invention or the scope of the subjoined claims.

10 Having thus described the invention, I claim:

1. In a rack of the character described, a main frame having legs for supporting it in an elevated position, a series of laterally spaced, upwardly arched strands connected at their ends to opposite sides of the frame, the end portions of all of said arched strands extending at an angle to the perpendicular, a plurality of strands extending transversely of the series of arched strands with their ends bent upwardly for attachment to the outside ones of said arched strands so as to bridge the spaces between the latter strands at a lower level than the tops of the arches, said arched and transverse strands collectively forming channels for supporting flat dishes leaning against the arched strands with their edges bearing on the transverse strands, and a truly perpendicularly arranged supporting and bracing strand connecting each transverse strand to each arched strand.

20 2. In a rack of the character described, a main frame having legs for supporting it in an elevated position, a series of laterally spaced, upwardly arched strands connected at their ends to opposite sides of the frame, a plurality of strands extending transversely of the series of arched strands with their ends bent upwardly for attachment to the outside ones of said arched strands so as to bridge the spaces between the latter strands at a lower level than the tops of the arches, each transverse strand being repeatedly reversely bent to provide a downward bend for each space it bridges between the arched strands with each bend forming an angle which is slightly offset laterally with respect to the transverse center of its particular space, and a supporting and bracing strand connecting each transverse strand to each arched strand at all of its high points of said reverse bends.

30 3. In a rack of the character described, a main frame having legs for supporting it in an elevated position, a series of laterally spaced, upwardly arched strands connected at their ends to opposite sides of the frame, and a plurality of strands extending transversely of the series of arched strands with their ends bent upwardly for attachment to the outside ones of said arched strands so as to bridge the spaces between the latter strands at a lower level than the tops of the arches, said arched and transverse strands collectively forming channels for supporting flat dishes leaning against the arched strands with their edges bearing on the transverse strands, said arched strands each having at one end portion of its top a downwardly bent angle formed to collectively provide a shelf extending across said dish channels to act as a support for a bowl when not obstructed by dishes in said channels.

40 4. In a rack of the character described, a main frame having legs for supporting it in an elevated position, a series of laterally spaced, upwardly arched strands connected at their ends to opposite sides of the frame and grouped at one end portion of said frame, a plurality of strands extending transversely of the series of arched strands with their ends bent upwardly for at-

tachment to the outside ones of said arched strands so as to bridge the spaces between the latter strands at a lower level than the tops of the arches, said arched and transverse strands collectively forming channels for supporting flat dishes stood on edge, said arched strands each having at one end portion of its top a depression formed therein so that collectively said depressions form a shelf extending across said dish channels to act as a support for a bowl when not obstructed by dishes in said channels, and an additional series of spaced strands extending transversely of and occupying a portion of the part of the frame not occupied by the arched strands and arranged in parallelism with said latter strands, said additional series of strands being shaped to form two stepped shelves for supporting bowls with one of these shelves being positioned to act as an extension of the bowl shelf formed in the arched strands.

5 5. In a rack of the character described, a main frame having legs for supporting it in an elevated position, a series of laterally spaced, upwardly arched strands connected at their ends to the opposite sides of the frame and grouped at one end portion of said frame, a plurality of strands extending transversely of the series of arched strands with their ends bent upwardly for attachment to the outside ones of said latter strands so as to bridge the spaces between the latter strands at a lower level than the tops of the arches, said arched and transverse strands collectively forming channels for supporting flat dishes stood on edge, said arched strands each having at one end portion of its top a depression formed therein so that collectively said depressions form a shelf extending across said dish channels to act as a support for a bowl when not obstructed by dishes in said channels, an additional series of spaced strands extending transversely of and occupying a part of the portion of the frame not occupied by the arched strands and arranged in parallelism with said latter strands, said additional series of strands being shaped to form two stepped shelves for supporting bowls with one of these shelves being positioned to act as an extension for the bowl shelf formed by the arched strands, and the final portion of the frame not occupied by the aforementioned two series of spaced strands having mounted therein a plurality of strands shaped to form a plurality of laterally sloping shelves for supporting cups, glasses, or the like, and for supporting a wire basket shaped to receive silverware.

35 6. In a rack of the character described, a main frame having legs for supporting it in an elevated position, a plurality of parallel dish receiving channels carried by the main frame, the sides of said channels being formed by a series of parallel, inverted, substantially U-shaped strands attached at their extremities to the main frame, the bottoms of said channels being formed by a series of parallel, substantially U-shaped strands arranged at right angles to and underlying the upper portions of the channel side forming strands with the extremities of their upwardly bent end portions attached to the upper portions of the outside ones of said channel side forming strands, the strands forming the sides of the channels each having formed in a portion of its top a downwardly bent angle, said angles collectively providing a shelf extending at right angles to said dish channels and acting as a support for a bowl, or the like, when not obstructed by dishes in said channel.

7. In a rack of the character described, a main frame having legs for supporting it in an elevated position, a plurality of parallel dish receiving channels carried by the main frame, the 5 sides of said channels being formed by a series of parallel, inverted, substantially U-shaped strands attached at their extremities to the main frame, the bottoms of said channels being formed by a series of parallel, substantially U-shaped 10 strands arranged at right angles to and underlying the upper portions of the channel side forming strands with the extremities of their upwardly bent end portions attached to the upper portions of the outside ones of said channel side forming strands, the strands forming the sides 15 of the channels each having formed in a portion of its top a downwardly bent angle, said angles collectively providing a shelf extending at right angles to said dish channels and acting as a 20 support for a bowl, or the like, when not obstructed by dishes in said channel, and an additional series of spaced parallel strands extending in parallelism with the channel side forming series of strands, said additional series of strands 25 shaped to form a shelf which is positioned to act as an extension of the bowl shelf formed by said angles of the channel side forming strands.

8. In a rack of the character described, a main frame having legs for supporting it in an elevated position, a plurality of parallel dish receiving channels carried by and occupying approximately one-half of the area of the main frame, the sides of said channels being formed 30

by a series of parallel, inverted substantially U-shaped strands attached at their extremities to the main frame, the bottoms of said channels being formed by a series of parallel, substantially U-shaped strands arranged at right angles to and underlying the upper portions of the channel side forming strands with the extremities of their upwardly bent end portions attached to the upper portions of the outside ones of said channel side forming strands, the strands forming the sides of the channels each having formed in a portion of its top a downwardly bent angle, said angles collectively providing a shelf extending at right angles to said dish channels and acting as a support for a bowl, or the like, when 15 not obstructed by dishes in said channels, an additional series of spaced parallel strands extending in parallelism with the channel side forming series of strands and occupying approximately one-half of the remaining area of the 20 main frame, said additional series of strands being shaped to form a shelf which is positioned to act as an extension of the bowl shelf formed by the said angles of the channel side forming strands, and the final portion of the main frame, 25 not occupied by the aforesaid series of strands, having mounted therein a plurality of strands shaped to form a plurality of laterally sloping shelves for supporting cups, glasses, or the like, and for supporting a wire basket shaped to receive silverware.

DONALD E. YOCHEM.
